UNITED STATES PATENT OFFICE.

WALTER BUSWELL, OF BRIDGEPORT, CONNECTICUT, ASSIGNOR TO STANDARD COM-
POSITOR AKTIENGESELLSCHAFT, OF BERLIN, GERMANY.

LINE-CASTING MACHINE.

Application filed April 11, 1925, Serial No. 22,262, and in Germany April 17, 1924.

This invention relates to line casting or linotype machines, and more particularly to an improved constructed and arranged mold adapted to be readily adjusted to various sizes of type bodies or slugs while at the same time maintaining the ideal base line of the characters invariable and constant.

Line-casting machines of the kind in question usually include type matrices assembled temporarily in line and suspended in a device known as the first elevator, so as to be lowered thereby to a position in front of a horizontally slotted mold which is thereafter advanced facewise against the said matrices which close the front of the mold while it is being filled from the rear with molten metal to produce a slug on the front edge of which the type characters are formed by the matrices, or in other words upside down when in the casting position, and heretofore it has been the practice to have characters of different sizes arranged to have a common alignment at the base of the characters.

The main object of the invention, as above stated, is to provide a mold which can be readily adjusted to various sizes of type bodies so that the ideal base line common to all characters of different size is always at the same distance from the center of the mold carrier. In carrying out the object of the invention I provide a frame having a substantially rectangular opening therein in which are mounted top and bottom parallelly arranged members to constitute the opposite side walls of the mold forming the mold slot, one of which member is adjustable relative to the other in the frame to vary the width of the mold slot for type bodies of different heights and thicknesses of slugs, with liners in the form of plates of a thickness to correspond with the height or thickness of the type body or slug to be cast inserted between said mold members, the opposed ends of which liners constitute the end walls of the slot in the mold, and a liner or plate proportional in thickness to the liners inserted between the mold members is inserted between the bottom mold member and the frame wall, adjustable means being provided to position the other mold member and whereby the mold slot will at all times be arranged so that the ideal base line of the characters when the matrices are presented

to the mold is always at the same distance from the center of the mold carrying wheel. 55 In other words, the opposite wall members of the mold are adjustable relative to each other to adapt the mold for the casting of slugs of variable thickness while maintaining the ideal base line of the type bodies or 60 characters, whatever the size of the latter may be, constant and invariable.

A further object of my invention is to provide a means for maintaining and securing the bar in the type slot during the trimming operation. With this object in view I provide in the casting mold a plurality of movable pins adapted to be caused to project slightly into the mold slot while the liquid metal is poured into the mold and while the mold is moved from the casting position to the ejecting position and to be withdrawn from the mold slot when the ejecting position is reached and the slug is to be ejected from the mold slot. 75

In the accompanying drawing forming a part of this specification I have shown, for purposes of exemplification, a preferred embodiment of the invention:

Figure 1 is a front elevation of part of a 80 mold wheel or carrier with a casting mold shown in full lines, in the casting position and with another mold indicated in dotted lines in the ejecting position; Figure 2 is a front elevation of a single mold shown on a 85 larger scale; Figure 3 is a fragmentary rear view of a mold likewise shown at an enlarged scale; Figure 4 is a cross sectional view of the mold taken on the line 4-4 of Figure 3; Figure 5 is a section taken on the line 5-5 90 of Figure 3; Figures 6 and 7 are a side view and a top view, respectively of one of the intermediate liners; Figures 8 and 9 are similar views of a liner for the various bodies of type; Figures 10 and 11 are a side view 95 and a top view, respectively, of a solid liner for the casting slot, and Figures 12 and 13 are a side view and an end view, respectively, of one of the securing pins.

Parts which are repeated in the several 100 figures bear the same reference characters in each case.

Referring to Figures 1 to 4 the mold carrier is shaped as usual to form a wheel 1 and adapted to carry a number of molds in recesses provided in the wheel for the purpose. 105

The molds are brought, by the rotation of the wheel, into the casting position and when the casting operation is finished, the charged mold is moved by a partial rotation of the 5 wheel 1, say one fifth or one fourth of a full revolution, into the ejecting position where the cast line is ejected by the ejector in the usual manner, the wheel being secured or locked against movement opposite the ejector 10 during the ejecting operation.

The casting mold comprises a frame 2 having a rectangular opening therein and recessed longitudinal edges 16 at the bottom face limit the movement of the frame into 15 and snugly fit a correspondingly shaped recess in the wheel so that the edge faces 16 will lie in intimate contact with the ground or polished surface of the wheel 1. The thus assembled parts are rigidly connected 20 by means of screws 3 or the like in the ordinary way. Mounted in the frame 2 are the top piece 4 and the bottom piece 5 to constitute the opposite wall members of the slot in the mold with the interchangeable 25 intermediate liners 6 and 7 between them, said liners being of a thickness equal to the height of the body of the desired type; the liner 6 is always of the same length, whereas the length of the liner 7 varies, as required 30 or desired, in order to vary thereby the form or length of the type bar. As regards the thickness of the liners 6 and 7 they are of the same dimensions in the pair used, but liners of different thickness are held in stock 35 for use according to the desired variations in the sizes of the bodies of type to be cast. Immediately below the bottom piece 5 an interchangeable liner 8 is inserted the size or thickness of which will vary in accordance with and be proportional to the thickness of the selected liners 6 and 7, that is to say, the thickness of the liner 8 is decreased proportionally with an increase in the thickness 40 of the two liners 6 and 7 and vice versa.

The frame 2 is provided with ledges 2' extending inward of the frame opening from the opposite end walls and at the back of the frame to constitute seating faces for the recessed faces 17 of the liners 6, 7 and 8 and for the top and bottom pieces 4 and 5 to snugly fit thereon and screws 18 are employed for securing the interchangeable parts in position in the mold frame against the said seating faces 2' of the frame 2. In 55 order that the screws 18 may act to press and hold together the assembled parts of the casting mold in accurate vertical direction or relationship, they are provided with a short cylindrical extension or pin 19 (Figure 2) engaging in a bore of the frame so as to act like a guiding holder. The casting mold constituted by the top and bottom pieces and the several liners is locked and pressed against the liner 8 by means of headless screws 20 threaded in the frame 2 and

bearing against the top piece 4. The liners 6 and 7 are provided with a laterally projecting nose 21 for engagement in a correspondingly formed recess in the bottom piece 5 for properly guiding and positioning 70 the same.

For the purpose of firmly holding the cast line or body in the casting slot of the mold during the trimming or truing up of the bottom of the line by means of a trimming 75 knife, pins 9 are provided in the top piece 4 or in the frame so as to project into the casting slot and to be surrounded, as far as they are within the slot, with the liquid metal. These pins 9 are cut out to form 80 oblique grooves 25 engaging with correspondingly inclined pegs or noses 13 or equivalent formations on a rod 10 slidably mounted in the top piece of the casting mold or in the frame. The outer end of the rod 85 10 is shaped to form a lip 12 for a stop 11 in the frame 2 to limit the travel of the rod. By the lengthwise movement of the rod 10 in the direction away from the stop 11 the pins 9 are moved in a direction to project 90 into the casting slot and by sliding the rod 10 in the other direction, that is towards the stop 11, the pins 9 are positively shifted to withdraw the pins from the casting slot. The reciprocatory movement is automatically imparted to the rod 10 by means of two 95 stationary stops or arms 14 and 23 mounted, as at 15 and 24, on the frame or bed of the machine. As the casting wheel 1 revolves from the casting position in the direction of the arrow shown in Figure 1 to the ejecting 100 position, the abutment 12 of the rod 10 will strike against the stationary arm 14 and the rod will thereby be arrested whilst the wheel 1 continues to revolve a short distance 105 beyond the arm 14. The pins 9 are thus withdrawn from the casting slot so that the cast line can be ejected from the mold in the usual manner. As the casting wheel then revolves in the direction opposite to 110 that shown by the arrow in Figure 1 the abutment 12 of the rod will strike against the stationary arm or stop 23 and the rod will be shifted thereby so that the pins 9 will again be caused to enter into the empty 115 casting slot. The liners 7 of variable lengths are provided with bores 22 for the reception of the reduced ends of the pins 9, as will be readily understood from Figure 2.

I have not attempted to explain all of the 120 parts and minute details of the machine since the latter, generally speaking, is of the usual construction and arrangement and the single parts not shown are of conventional type so that the invention as described 125 and shown will be fully understood by those to whom this specification is addressed and who are versed in the art.

I also deem it unnecessary to reiterate 130 the operation of the machine, for the opera-

tion of the single parts in question has been described in detail. Nor is it deemed necessary to set forth the advantages which the invention possesses, since they will be apparent to those skilled in the art to which this invention relates. Furthermore, the invention is not limited to the exact details of construction and arrangement shown and described as it will be obvious that various modifications may be made and still come within the scope of the invention.

What I claim is:—

1. In a mold for line casting machines, an open frame adapted to be detachably mounted and supported upon the mold carrier, a pair of parallel bars to constitute the opposite walls of a mold slot mounted in the opening of the frame to have adjustment one relative to the other, liners interposed between said bars, said liners having a combined length less than the bars and releasably supported at one end by the frame to extend inwardly from opposite ends of the mold bars and cooperate with the bars to form the mold slot, and a third liner interposed between one of the mold bars and the wall of the frame opening for the purpose specified.

2. In a mold for line casting machines as claimed in claim 1, means to releasably secure the mold bars and liners in the frame.

3. In a mold for line casting machines as claimed in claim 1, means carried by the frame and cooperating with the other mold bar to exert a force thereon to releasably clamp the mold bars and liners in juxtaposed relation in the frame, and means to releasably secure the bars and liners against lateral displacement from the frame.

4. In a mold for line casting machine as claimed in claim 1, means to releasably secure the mold bars and liners in the frame, and means for releasably retaining a cast body in the mold slot for the purpose specified.

5. In a mold for line casting machine as claimed in claim 1, means to releasably secure the mold bars and liners in the frame, and pins slidably carried by one mold bar to have movement transversely into and out of the mold slot to releasably retain a cast body therein for the purpose specified.

6. In a mold for line casting machine as claimed in claim 1, means to releasably secure the mold bars and liners in the frame, pins slidably carried by one mold bar to have movement transversely into and out of the mold slot to releasably retain a cast body therein, and means to actuate said pins.

7. In a mold for line casting machine as claimed in claim 1, means to releasably secure the mold bars and liners in the frame, pins slidably carried by one mold bar to have movement transversely into and out of the mold slot to releasably retain a cast body

therein, said pins having an oblique groove in a portion extending from the mold bar, and a rod mounted in the frame to have longitudinal reciprocatory movement and arranged with means to engage in the pin 70 grooves and adapted to move the pins into and out of the mold slot as the rod is reciprocated.

8. In a mold for line casting machines as claimed in claim 1, screws threaded into the opposite wall of the frame and adapted to abut the other mold bar to clamp the mold bars and liners in juxtaposed relation in the frame, and means to secure the mold bars and liners against lateral displacement from 80 the frame.

9. In a mold for line casting machines as claimed in claim 1, screws threaded into opposite wall of the frame and adapted to abut the other mold bar to clamp the mold bars and liners in juxtaposed relation in the frame, and screws having threaded connection with the frame and overlapping the ends of the juxtaposed mold bars and liners to hold the same against lateral displacement 90 from the frame.

10. In a line casting machine, a rotary mold carrier, a mold frame detachably connected to and supported by said carrier, and a mold releasably mounted in said frame 95 comprising a bottom piece and a top piece, and liners of various thickness adapted to be inserted between said bottom piece and said top piece.

11. In a line casting machine as claimed 100 in claim 10, means for securing the mold pieces in the frame, and means to releasably retain a cast body in the mold slot.

12. In a line casting machine, a rotary mold carrier, a mold frame detachably connected to and supported by said carrier, a mold removably mounted in said frame comprising a bottom piece and a top piece, liners interposed between said bottom and top pieces to arrange the mold slot between 105 110 said pieces to adapt the mold to a particular type body to be cast, means for securing said bipartite mold and the liners in the frame, pins slidably mounted in the frame adapted to be projected through openings 115 in one of the pieces into the mold slot, and a rod in the frame for actuating said pins.

13. A line casting machine as claimed in claim 12, wherein the pin actuating rod is reciprocatory longitudinally in the frame 120 and arranged with means to co-operate with the pins to project the pins into the mold slot when moved in one direction and withdrawing the pins from the mold slot when moved in the opposite direction.

14. A line casting machine as claimed in claim 12, wherein the pin actuating rod is reciprocatory longitudinally in the frame and arranged with means to co-operate with the pins when moved longitudinally to pro- 130

ject the pins into and withdraw the same from the mold slot, said rod having a lip at one end for engagement by a fixed stop as the mold carrier is moved in one direction to move the rod in one direction to project the pins into the mold slot, and when the mold carrier is moved in reverse direction

said lip engaging with another fixed stop to move the rod in the opposite direction to withdraw the pins from the mold slot. 10

In testimony whereof I have affixed my signature.

WALTER BUSWELL.
